UNITED STATES PATENT OFFICE.

WILLIAM J. JEFFRIES AND SCOTT W. GIBBONS, OF PORTLAND, OREGON.

AUTOMATIC PAPER-FOLDING MACHINE.

Application filed December 5, 1927. Serial No. 237,837.

This invention relates to improvements in automatic paper folding machines, one object of the invention being the provision of a portable machine adapted particularly for use in folding circulars, pamphlets and the like in mail-order houses, the same being so constructed that the sheet may be folded once, twice or thrice upon itself, and as may be desired.

Another object of this invention is the provision of a machine of this character provided with a plurality of folding mechanisms operable in succession, but in which any one of said mechanisms may be rendered inoperative at will or selectively so that the paper will be folded either with a single, double or treble fold, as desired.

Another object of this invention is the provision of a machine of this character which is simple, inexpensive and durable in construction and thoroughly efficient and practical in use.

In the accompanying drawings:—

Figure 1 is a side elevation of the complete machine.

Figure 2 illustrates in side elevation one folding mechanism, dotted lines showing the frame and the cam carried by the roller to operate the same.

Figure 3 is a top plan view of one of the folding mechanisms per se.

Figure 4 is a side elevation of the cam and its roller.

Figure 5 is a top plan view thereof.

Referring to the drawings, the numeral 10 designates the framework which has mounted therein the respective cooperating folding rollers 11 and 12, 13 and 14, 15 and 16, and the drive roller 17 and the belt-tensioning roller 18, there being eight rollers around which the operating belt 19, in reality the drive member for most of the rollers, is trained. In order to operate the belt, and, consequently, the rollers, there is provided a small electric motor 20 which, through the belt 21, operates a large pulley 21' mounted upon the shaft 22, the small pulley 23 carried upon said shaft operating through the belt 24 another large pulley 25 which, in turn, is mounted upon a shaft 26 and carries a small pulley 27. A belt 28 transmits power from the pulley 27 to the pulley 29 upon the roller 17. Thus, it will be seen that the motor 20 operates the roller 17, and through the medium of the transmission and folding

belt 19, the various rollers of the present mechanism.

Mounted upon each of the rollers 11, 13 and 15, and as particularly illustrated in Figures 2, 3, 4 and 5, is a cam track 30 which is provided with the in-curved end 31 spaced from the opposite end of the track, the purpose of which is to receive the roller 32 of the lever 33 which is pivoted, as at 34. The opposite end of the lever 33 is connected by a link 35 to the U-shaped folding frame 36, which is pivoted as at 36' and 36^a to the frame of the machine, the pivot 36^a being in the nature of a clamping device so that the folding frame may be elevated and locked in elevated position. The downwardly curved ends 37 of the frame carry the folding terminal or blade 38 while the spring 39 operates in opposition to the cam track 30 to move the folding frame downwardly and into engagement with the sheet of paper to be folded and in between the belt 19 and the folding rollers 12, 14 or 16. It will thus be seen that as the respective rollers 11, 13 and 15 are rotated, the lever 33, due to the engagement of its roller 32 with the cam track 30, will cause the folding frame to be elevated and held away from the folding mechanism, that is, the belt and its respective roller, until the roller passes off of the concentric end of the track, and due to the spring 39 the blade 38 is brought downwardly and into engagement with the sheet to be folded, as particularly illustrated in Figure 2. The present mechanism is of a light construction and as the machine is very small and adapted for office use, the blade 38 has imparted to it a light tap in going down due to the weight of the same and the tension of the spring 39, so that the operator may, at will, prevent the movement of the frame either after the sheet of paper has been misplaced, or, if it is desired to render any one of the particular folding mechanisms inoperative. This is done by the elevating of the blade and the tightening of the connection 36^a, and, if desired, the removal of the spring 39.

In order that the paper may be properly fed to the folding mechanism, either one mechanism or all three, as illustrated, there is the feed-in table 40 at the upper end of the machine upon which the stack of paper may be placed and one sheet at a time placed upon the belt 19 above the roller 11, at which point the belt tends to move the paper and

deliver it across the space between the rollers 11 and 12, so that the paper rests upon the shelf 41 and against the respective adjustable guides 42 and 42', said shelf 41 being supported in the brackets 43, and said brackets carrying the fixed blade 44 which extends transversely of the belt 19 and in such a position as to prevent the paper fed upon the belt from being carried beyond this point by the belt and acting as a guide to direct the paper from the belt over onto and upon the shelf 41.

Simultaneously with the placing of the edges of the papers against the edges of the guides 42 and 42', the folding blade 38 is brought downwardly and engages the paper intermediate of its ends, a portion still resting upon the bar or blade 44, producing the fold and delivering the paper between the belt and the under side of the roller 12. The folded paper is then carried beneath the roller 12 and upon the belt 19 and over the roller 13, where the blade 44 of this folding mechanism directs the same over and upon its respective shelf 41, the folding blade 38 of the second mechanism operating in a similar manner to produce the second fold in the sheet and the delivery thereof between the belt 19 and the roller 14, the belt carrying the thus folded sheet onward and over the roller 15 where again the blade 44 of the third folding mechanism delivers the sheet upon the shelf 41 to be retained thereupon during the folding operation when the last blade 38 is brought into play and causes the sheet to be again folded and directed between the roller 16 and the belt 19 and carried therefrom and over the roller 17 into the directing chute 45 and out of the machine.

Where it is desired to use only one folding mechanism, the two upper ones are rendered inactive, and where it is desired to fold the paper twice, the upper mechanism is rendered inactive.

As it is desirable that the respective rollers 11, 13 and 15 be operated in consonance or synchronism, there is placed upon the respective shafts thereof the sprocket wheels 47, 48 and 49 around which is trained a sprocket chain 50. Thus, as the rollers are rotated by their belt, the chain 50 will keep them in proper stepped or timed relation, and, consequently, the cam tracks 30 will be operated so that the folding mechanism will always be in time.

From the foregoing description taken in connection with the drawings, it is evident that with a device of this character pamphlets and other sheets of advertising or other matter may be folded in a rapid and thorough manner, and that with the present mechanism as illustrated, said sheet may be folded either once, twice or thrice, according to the length thereof, and the desired size of the finally folded pamphlet. This machine is especially adapted for use in small

mail-order houses where a certain number of pamphlets and serial letters are sent out and where an exceedingly large and heavy machine is impracticable.

We claim:—

1. A paper folding machine including a frame, a plurality of pairs of paper delivering and folding rollers journaled therein, a belt operably connected to all of said rollers, a final delivering roller operably connected to the belt, means operably connected to said rollers whereby the belt and other rollers are operated, a paper folding mechanism, one to each pair of rollers, operably associated with one roller thereof for delivering a folded sheet between the belt and one of the rollers, said latter mechanism including a spring-actuated folding frame, and cooperative means carried by said frame and one of said rollers whereby the frame is moved away from folding position. 70

2. A paper folding machine including a frame, a plurality of pairs of paper delivering and folding rollers journaled therein, a belt operably connected to all of said rollers, a final delivering roller operably connected to the belt, means operably connected to said rollers whereby the belt and other rollers are operated, a paper folding mechanism, one to each pair of rollers, operably associated with one roller thereof for delivering a folded sheet between the belt and one of the rollers, said latter mechanism including a spring-actuated folding frame, and cooperative means carried by said frame and one of said rollers whereby the frame is moved away from folding position, and selective means operable at will for rendering the folding member inoperative. 80

3. The combination with a pair of rollers and a belt cooperatively associated therewith to form one member of a folding mechanism and a delivery means for sheets of paper, of a paper folding and delivering means including a pivotally mounted U-shaped frame, the connecting portion of which is adapted to be moved into and out of the meeting point between the belt and one of said rollers, said frame being resiliently biased toward folding position, means for moving said frame outwardly and away from folding position, including a lever, and cooperative operating means carried by one end of said lever and operably connected to one of said rollers. 105

4. The combination with a pair of rollers and a belt cooperatively associated therewith to form one member of a folding mechanism and a delivery means for sheets of paper, of a paper folding and delivering means including a pivotally mounted U-shaped frame, the connecting portion of which is adapted to be moved into and out of the meeting point between the belt and one of said rollers, said frame being resiliently biased toward folding position, means for moving said frame out- 110

wardly and away from folding position, including a lever, cooperative operating means carried by one end of said lever and operably connected to one of said rollers, means disposed in the path of the belt for stripping the sheet therefrom previous to the folding operation, and adjustable means for receiving

the forward edge of the sheet and positioning it for the reception of the folding frame.

In testimony whereof we have hereunto set 10
our hands.

WILLIAM J. JEFFRIES.
SCOTT W. GIBBONS.
